(57) CLAIM

The ornamental design for a wheeled cargo organizer, as shown and described.

DESCRIPTION

FIG. 1 is a front perspective view of a wheeled cargo organizer according to my new design in a closed state;

FIG. 2 is a left side elevation view;

FIG. 3 is a right side elevation view;

FIG. 4 is a front elevation view;

FIG. 5 is a rear elevation view;

FIG. 6 is a top plan view;

FIG. 7 is a bottom plan view; and,

FIG. 8 is a front perspective view of the cargo organizer with the upper compartment and lower side compartment in an open state.

The broken lines depicting the logo, side handles, support ribs, wheels, zipper compartment enclosing a retractable handle and zipper tabs are for illustrative purposes only and form no part of the claimed design.
